Term of patent 14 years

(Cl. D34—5)

FIG. 2

FIG. 1 is a front view of the golf tee showing my new design;

FIG. 2 is a top view of the golf tee;

FIG. 3 is a left side view of the golf tee; and

FIG. 4 is a right side view of the golf tee.

The broken line showings of a golf ball in FIGS. 1, 3 and 4 are for illustrative purposes only.

My design comprises the 6 tapered legged golf tee having a miniaturized centrally located golf ball representation. I claim:

The ornamental design for a golf tee, as shown and described.
